FLUID-OPERATED FREE PUMP WITH
PACKING DEVICERalph F. McArthur, Huntington Park, Calif., as-
signor, by mesne assignments, to Dresser Equip-
ment Co., Cleveland, Ohio, a corporation of Ohio

Application January 16, 1950, Serial No. 138,909

3 Claims. (Cl. 103—46)

1

My invention relates to a fluid-operated free pump having packing means for preventing fluid flow past the exterior thereof and, more particularly, to a packing device for this or other purposes, a primary object of the invention being to provide an improved packing device.

A well pumping system incorporating a fluid-operated free pump normally includes at least two tubings set in a well, which may be an oil well, for example. One of the tubings of such a system is adapted to convey an operating fluid, such as clean crude oil, under relatively high pressure downwardly to the pump to operate it and may be termed a power tubing. The other tubing of such a system is adapted to convey the fluid discharged by the pump upwardly in the well to the surface of the ground and may be termed a production tubing. The fluid-operated free pump is movable hydraulically through one of the tubings between an operating position at the lower end thereof and the surface of the ground. The tubing through which the pump is movable is preferably the power tubing and the pump will be regarded as movable through the power tubing hereinafter for purposes of illustration, although it will be understood that the pump may be movable through either the power or production tubings without departing from the spirit of the invention.

In a well pumping system of the foregoing nature, the operating fluid is admitted to the pump from the power tubing at a point adjacent the upper end of the pump and the fluid discharged by the pump is discharged into the power tubing at a point or points below the point of operating fluid intake. In order to permit flow of the fluid discharged by the pump from the power tubing into the production tubing, the two tubings are conventionally interconnected in fluid communication at their lower ends. Consequently, it is necessary to provide a packing device for separating the operating and production fluid columns, i. e., to prevent flow between the operating and production fluid columns through the annular clearance between the exterior of the pump and the interior of the power tubing, which is the purpose of the present invention.

Normally, the operating and production fluid columns are separated by a packing device, which may be a simple O-ring, adapted to engage a relatively short sealing collar in the line of the power tubing when the pump is in its operating position. The internal diameter of the sealing collar is preferably less than the internal diameter of the power tubing as a whole so that a clearance

is provided between the O-ring and the internal wall of the power tubing when the O-ring is out of engagement with the sealing collar. This prevents damage to the O-ring during movement of the pump between its operating position and the surface of the ground. However, in some instances it is desirable to connect an attachment to the lower end of the pump so that the O-ring normally separating the operating and production fluid columns is located above the sealing collar when the pump is in its operating position, whereupon the O-ring can no longer serve as a separating means for the two columns. Consequently, it is an important object of the present invention to provide a fluid-operated free pump having a substitute packing device thereon for separating the operating and production fluid columns when the packing device normally employed is inoperative.

Another object is to provide a fluid-operated free pump having thereon a packing device which is disposed between the point of operating fluid intake and the point or points of fluid discharge and which is adapted to engage the internal wall of the power tubing at a point above the sealing collar.

Another object is to provide a packing device which includes a packing element of a readily deformable material which is adapted to expand radially into fluid-tight engagement with the internal wall of the power tubing upon application of a fluid pressure thereto.

Another important object of the invention is to provide a packing device including a main backing element which is disposed on the low pressure side of the packing element and which is also formed of a deformable material so that it is capable of engaging the internal wall of the power tubing in a positive manner to prevent extrusion of the material of the packing element therewith upon application of pressure to the packing element.

An object related to the preceding one is to provide a main backing element which is formed of a material that is less deformable than that of the packing element so as to minimize any tendency of the main backing element to extrude. Preferably, the packing element is formed of a nonmetallic packing material, such as rubber or like material, and the main backing element is formed of a metallic material.

Another important object is to provide a substantially nondeformable auxiliary backing element which is located on the low pressure side of the deformable main backing element to prevent

extrusion of the main backing element between the auxiliary backing element and the power tubing.

The foregoing objects of the present invention, together with other objects thereof which will become apparent, may be attained through the utilization of the exemplary embodiments of the invention which are illustrated in the accompanying drawing and which are described in detail hereinafter. Referring to the drawing:

Fig. 1 is a utility view of a fluid-operated free pumping system which embodies the invention;

Fig. 2 is an enlarged, vertical sectional view taken along the broken line 2—2 of Fig. 1;

Fig. 3 is a transverse sectional view taken along the broken line 3—3 of Fig. 2;

Fig. 4 is a vertical sectional view which is similar to Fig. 2 but which illustrates another embodiment of the invention; and

Fig. 5 is a transverse sectional view taken along the broken line 5—5 of Fig. 4.

Referring particularly to Fig. 1, the numeral 10 indicates a well casing which may be set in an oil well, for example, and which is open at its lower end to an oil producing formation adjacent the well. Extending downwardly into the well casing 10 are power and production tubings 11 and 12 which are threaded at their lower ends into a fitting 13 having therein a passage 14 for interconnecting the power and production tubings in fluid communication. In the particular construction illustrated, a gas anchor 15 encloses the lower ends of the production tubings 11 and 12 and the fitting 13 and is secured to the fitting 13 by a bolt 16. Seated in the fitting 13 in alignment with the power tubing 11 is a standing valve assembly 17 which provides a seat for a fluid-operated free pump 18 having an attachment 19 connected to its lower end. As is well known in the art, the pump 18 is movable hydraulically between the surface of the ground and its operating position wherein it is seated on the standing valve assembly 17, the pump being movable through the power tubing 11 from the surface into its operating position by an operating fluid pressure applied to the upper end thereof, and being movable from its operating position to the surface by an operating fluid pressure applied to the lower end thereof by way of the production tubing 12 and the passage 14. Fluid flow past the pump during movement upwardly through the power tubing 11 is prevented by packers 20 on a packer mandrel 21 which extends upwardly from the body of the pump. The packers 20 are conventional and form no part of the present invention.

Disposed in the line of the power tubing 11 is a sealing collar 22 which, in effect, constitutes a coupling between two sections of the power tubing. Pressed or otherwise secured in the sealing collar 22 is a liner 23 having an internal diameter which is less than that of the power tubing. When the pump 18 is used in the normal manner without the attachment 19, the columns of fluid in the power and production tubings 11 and 12 are separated by a packing means, such as an O-ring 24, which engages the inner periphery of the liner 23, the O-ring being carried by the pump between the point of operating fluid intake and the point or points of fluid discharge so as to prevent intermingling of the operating and production fluid columns by way of the annular clearance provided between the pump and the power tubing. However, as illustrated in Fig. 1, when the attachment 19 is employed in

conjunction with the pump 18, the O-ring 24 is located above the liner 23 so that it is inoperative to separate the operating and production fluid columns, the reason for this being that, as previously indicated, the external diameter of the O-ring is preferably less than the internal diameter of the power tubing so as to prevent damage to the O-ring during movement of the pump between its operating position and the surface of the ground.

In accordance with the present invention, the pump 18 carries a packing device 30 which is located between the point of operating fluid intake and the point or points of fluid discharge and which engages the internal wall of the power tubing 11 to separate the operating and production fluid columns when the O-ring 24 is inoperative to do so. Referring particularly to Fig. 2, the packing device 30 includes a packing element 31 which encompasses the packer mandrel 21 and which engages the lower end of a sleeve 32 encompassing and suitably secured to the packer mandrel to prevent upward movement of the packing element along the mandrel. The packing element 31 is generally cup-shaped and is positioned on the mandrel 21 with its open end facing upwardly toward the higher pressure applied thereto, i. e., toward the operating fluid column. The packing element 31 is provided adjacent its rim with an annular surface 33 which lightly engages the internal wall of the power tubing 11 when the fluid pressures above and below the packing element are substantially equal. The packing element 31 is formed of a readily deformable material of a rubber-like nature, a rubber-like material, such as neoprene, which is oil resistant preferably being employed for oil well pumping systems.

Since the cup-shaped packing element 31 faces upwardly toward the operating fluid column, it will be apparent that, when the pressure of the operating fluid is increased to a relatively high value to operate the pump 18, the annular portion 34 of the packing element is deformed radially outwardly into fluid-tight engagement with the internal wall of the power tubing 11 so as to separate the operating and production fluid columns, which is an important feature of the invention. In order to prevent downward extrusion of the material forming the packing element 31 by the relatively high operating fluid pressure thereabove, I provide the packing device 30 with a deformable main backing element 37 which is preferably formed of a relatively soft metal such as copper, for example. In the embodiment under consideration, the main backing element 37 is also generally cup-shaped and faces in the same direction as the cup-shaped packing element 31 with its rim 38 deformed inwardly and embedded in the material of the packing element. As will be apparent, since the packing element 31 is formed of a readily deformable material of a rubber-like nature, the base portion 39 of the packing element is compressed longitudinally by the operating fluid pressure thereabove with the result that the base portion of the packing element expands radially outwardly. Such radially outward expansion of the base portion 39 of the packing element 31 deforms the main backing element 37 radially outwardly into engagement with the internal wall of the power tubing 11 so as to reduce substantially to zero any annular clearance through which the material of the packing element 31 might be extruded by the op-

5

erating fluid pressure thereabove, which is an important feature of the invention.

The cup-shaped main backing element 37 is provided with an annular base portion 42 seated against a substantially nondeformable, auxiliary backing element 40 which encompasses the packer mandrel 21 and which is in turn seated against a fitting 41 threaded onto the upper end of the body of the pump 18. The fitting 41 provides a recess 43 into which a sleeve portion 44 of the main backing element 37 and an annular portion 45 of the packing element 31 extend, this arrangement providing a fluid-tight seal with the backing element 40. The auxiliary backing element 40 serves to prevent downward extrusion of the main backing element 37, which is another important feature of the invention. Since the main backing element 37, while deformable, is materially less deformable than the packing element 31, an appreciable clearance between the auxiliary backing element 40 and the internal wall of the power tubing 11 may be provided, such clearance being desirable to facilitate movement of the pump 18 through the power tubing, and particularly through sections of the power tubing which are of smaller internal diameter than the nominal value.

It will be understood that when the pump 18 is being moved through the power tubing 11, the fluid pressures above and below the packing device 30 are approximately equal, in which case the parts of the packing device assume substantially the positions shown in Fig. 2 so that the packing element 31 engages the internal wall of the power tubing 11 only lightly throughout the area of the annular surface 33 so as to minimize wear of the packing element when running the pump into and out of the well. The packing element 31 may not engage the power tubing 11 at all when the pump is being run out of the well in particular, the reason for this being that the fluid pressure applied to the lower end of the pump to move it upwardly out of the well tends to deform the annular portion 34 of the packing element 31 inwardly out of engagement with the power tubing. In this case, the pressure applied to the pump to move it upwardly acts on the aforementioned packers 20.

Referring to Figs. 4 and 5, the embodiment of the invention illustrated therein is similar to that discussed previously and corresponding parts are identified by corresponding reference numerals plus the suffix "a." The packing device 30a differs from the packing device 30 principally in the main backing element 37a, the latter comprising a pair of superimposed, annular, wire-brush-like members 42a which encompass the packer mandrel 21a and which engage the internal wall of the power tubing 11a. Each wire-brush-like member 42a comprises a plurality of U-shaped bristles which are looped around an annulus 43a and which extended radially outwardly into engagement with the power tubing 11a. After the U-shaped bristles have been placed on each annulus 43a, they are retained thereon by an annular element 44a of channel shaped cross section. The two members 42a are held in place by being clamped between the lower end of the base portion 39a of the packing element 31a and the upper end of the auxiliary backing element 40a.

Preferably, the diameter of the members 42a is normally slightly greater than the internal diameter of the power tubing 11a so that, when the pump 18a is inserted into the power tubing, the bristles of the members 42a are bent upwardly or

6

trail slightly. Consequently, when the packing element 31a is deformed longitudinally by the operating fluid pressure thereabove, it engages the bristles of the members 42a and tends to some extent to return to horizontalness, thereby increasing the bearing pressure at the interface between the bristles and the internal wall of the power tubing. This insures that the main backing element 37a will prevent extrusion of the packing element 31a. As in the previous embodiment, the members 42a of the main backing element 37a are materially less deformable than the packing element 31a so that, while the auxiliary backing element 40a prevents extrusion of the members 42a, an appreciable clearance between the auxiliary backing element 40a and the power tubing 11a may be provided to facilitate movement of the pump 18a through the power tubing, and particularly through undersize sections of the power tubing.

Thus, the present invention provides a packing device which comprises a readily deformable packing element for providing a fluid-tight seal, a less deformable main backing element for preventing extrusion of the packing element, and a substantially nondeformable auxiliary backing element for preventing extrusion of the main backing element.

Although I have disclosed two exemplary embodiments of my invention herein for purposes of illustration, it will be understood that various changes, modifications and substitutions may be incorporated in the embodiments disclosed without departing from the spirit of the invention and I hereby reserve the right to all such changes, modifications and substitutions as properly come within the scope of the invention.

I claim as my invention:

1. In a well pumping system which includes a tubing set in the well and provided with a seat and a sealing collar above said seat, and which includes a fluid-operated free pump movable through said tubing between an operating position at the lower end thereof and the surface of the ground, the external diameter of said pump being less than the internal diameter of said tubing to provide an annular clearance therebetween, said pump being adapted to seat on said seat and carrying a sealing element which engages said sealing collar when said pump is seated on said seat, the internal diameter of said sealing collar and the diameter of said sealing element being less than the internal diameter of said tubing to prevent engagement of said sealing element with said tubing, and said pump having an attachment connected to the lower end thereof and adapted to seat on said seat so that said sealing element is spaced above said sealing collar when said attachment is seated on said seat, the combination of: an annular packing element carried by said pump above said sealing element and engageable with said tubing to prevent fluid flow through said annular clearance between said pump and said tubing, said packing element being formed of a deformable material; and backing means carried by said pump below and in contact with said packing element.
2. The combination defined in claim 1 wherein said backing means includes a main backing element for said packing element disposed below and in contact with said packing element and formed of a deformable material which is less deformable than that of said packing element, said backing means including an auxiliary backing element below and in contact with said main

backing element and formed of a substantially nondeformable material.

3. In a well pumping system which includes a tubing set in the well and provided with a seat and a sealing collar above said seat, and which includes a fluid-operated free pump movable through said tubing between an operating position at the lower end thereof and the surface of the ground, the external diameter of said pump being less than the internal diameter of said tubing to provide an annular clearance therebetween, said pump being adapted to seat on said seat and carrying a sealing element which engages said sealing collar when said pump is seated on said seat, the internal diameter of said sealing collar and the diameter of said sealing element being less than the internal diameter of said tubing to prevent engagement of said sealing element with said tubing, and said pump having an attachment connected to the lower end thereof and adapted to seat on said seat so that said sealing element is spaced above said sealing collar when said attachment is seated on said seat, the combination with the foregoing elements of an annular sealing means carried by said pump

5 above said sealing element and engageable with said tubing to prevent fluid flow through said annular clearance between said pump and said tubing, said sealing means being expansible radially into engagement with said tubing by pressure thereabove.

RALPH F. McARTHUR.
